UNITED STATES PATENT OFFICE.

STEPHEN W. SMITH, OF DOUGLASVILLE, GEORGIA.

ROAD-MACHINE.

No. 876,846.

Specification of Letters Patent.

Patented Jan. 14, 1908.

Application filed May 28, 1907. Serial No. 376,203.

To all whom it may concern:

Be it known that I, STEPHEN W. SMITH, citizen of the United States, residing at Douglasville, in the county of Douglas and State of Georgia, have invented certain new and useful Improvements in Road-Machines, of which the following is a specification.

This invention contemplates certain new and useful improvements in machines for grading, smoothing or otherwise working roads, and the invention consists in certain constructions, arrangements and combinations of the parts which I shall hereinafter fully describe and then point out the novel features in the appended claims.

For a full understanding of the invention and the merits thereof and also to acquire a knowledge of the details of construction of the means for effecting the result, reference is to be had to the following description and accompanying drawings, in which:

Figure 1 is a top plan view of my improved road machine. Fig. 2 is a side elevation thereof. Fig. 3 is a longitudinal sectional view on the line 3—3 of Fig. 1. Fig. 4 is a transverse sectional view on the line 4—4 of Fig. 1. Fig. 5 is a detail side elevation, partly broken away, of a portion of the extensible front beam of the frame work. Fig. 6 is a detail transverse section on the line 6—6 of Fig. 5. Fig. 7 is an enlarged detail sectional view hereinafter specifically referred to. Fig. 8 is a top plan view of the steering elements. Fig. 9 is a detail view of one end of a bolster. Figs. 10 and 11 are detail top and front views of the worm gear, and Fig. 12 is a detail view of one of the scrapers.

Corresponding and like parts are referred to in the following description and indicated in all the views of the drawings by the same reference characters.

My improved road machine comprises a wagon or vehicle and the operating framework and actuating parts carried by the said vehicle.

The vehicle includes traveling wheels 1, rear and front axles 2 and 3, and reaches 4 of which there are two shown, spaced from each other and which are connected at their rear ends to the rear axle 2 and at their front ends to the bolster 5. Said bolster is provided with upwardly and outwardly projecting elevated ends 6, which extend over the front wheels and give sufficient clearance to

the latter in turning. A platform 7 is supported by the pair of reaches 4, reaches extending therethrough, as indicated by dotted lines in Figs. 1 and 3, and the operator or driver stands on this platform and manipulates the different actuating elements of the apparatus. 8 designates a steering rod which projects upwardly from the platform and which is provided at its upper end with a hand wheel 9 and at its lower end with a pinion 10, the latter meshing with a toothed steering segment 11 secured to the front axle 3 at opposite sides of the fifth wheel. 12 designates a detent wheel which is fast on the lower end of the rod 8 and which is designed to be engaged by a foot operated detent 13.

The frame work which is supported by the vehicle, above described, and which is adapted to be elevated or suspended therefrom when not operating, and be let down into engagement with the road when operating, includes a front cross beam 14 which is formed in three sections. To the intermediate or main section 15, the draft tongue 16 is secured. 17 designates the two side or extensible sections that are slidingly connected to the main section 15 by means of coupling sleeves 18. Each of the extensible side sections 17 of the front cross beam is provided with a rack 19, and pinions 20 are journaled in the main section and mesh with said racks. Ratchets 21 are secured on the shafts of the respective pinions 20 and are adapted to be engaged by double pawls 22 carried by levers 23 fulcrumed on said shaft. Hence it will be seen that by manipulating either of the two hand levers 23 or both of them, either one or both of the sections 17 may be extended laterally or retracted. The frame work also includes longitudinal beams 24 which are secured, preferably by inwardly extending angular portions to the ends of the extensible sections 17 of the front cross beam. These longitudinal beams 24 converge towards their rear ends as shown and are connected by hinges 25 to the rear cross beam 26. Both of the longitudinal beams 24 and the rear cross beam 26 are provided with inwardly extending cutting or scraping edges 27 as clearly illustrated in the drawings. The longitudinal beams 24 carry near their front ends, and preferably at the angle of their main portions with their inwardly extending front portions,

scraping blades 28 that are secured thereto by standards 29 and that are preferably provided with returned front edges 30 extending around the front edge of the scraping or cutting portions 27 of said longitudinal beams, as best seen in Fig. 12. These sliding scrapers are sharp and are provided for the purpose of cutting against road banks and for the further purpose of steadyng the machine 10 in its operation. Coupling irons 31 are connected to the main sections 15 of the front cross beam, and converge towards their rear ends, such ends being connected together, preferably as an integral structure, and being 15 mounted to slide vertically in a slotted guide frame 32 preferably supported on the bolster and having its ends connected to the upper and lower ends of the king bolt. Chains 33 are connected at their lower ends in any suitable 20 way to the respective longitudinal beams 24 near the front ends of the latter and the said chains extend upwardly through slots 34 in laterally movable slides 35. The upper ends of the respective chains are adapted 25 to wind over grooved sheaves 36 fast on the outer ends of the shafts 37. These shafts are journaled in bearings 38 on the slides 35, and the said bearings may be formed by turning the ends of said slides upwardly 30 as shown, or in any desired manner. The inner ends of the shafts 37 are provided with hand wheels 39. The slides 35 are mounted in guide ways 40 secured to the upwardly projecting ends 6 of the bolster 5, and bearing rollers 41 preferably extend over the 35 slides, so as to assist in guiding them properly. Other rollers 42 are journaled underneath the slides at the extreme outer ends of the bolster, and these latter rollers are 40 preferably fast on the same shaft with heads 43, the latter being provided with sockets 44 for the reception of a suitable rod or other tool to assist in moving the slides in and out as the frame work is 45 extended or contracted laterally, in case the said slides do not adjust themselves.

Worm gears 45 are splined on the respective shafts 37 and are adapted for meshing engagement with worms 46 on the shafts 47. 50 These shafts 47 are journaled in bearings on forked brackets 48 secured to the bolster as shown. Each bracket embodies a stationary arm 49 formed with a bearing for the said shaft, and a vertically movable arm 50 forming the other bearing. This latter arm is provided with a rack 51 adapted to be engaged by segments 52 on an actuating shaft 53. This shaft is provided with a hand lever 54 carrying a detent bar 55 for engagement with a quadrant 55. By manipulating the hand lever it is manifest that the movable arm 50 may be raised or lowered so as to disengage the worm from the worm gear or vice versa. The worm 65 gears 45 are preferably held relatively sta-

tionary as the shafts 37 are carried in and out on the slides, and the means for holding said worm gears stationary comprises in the present instance a pair of rollers carried on a fork 45 secured to the stationary arm 49 70 of the bracket 48.

The reaches 4 are provided at their rear ends with arches 56. A chain 57 is secured at its lower end to the rear cross beam 26, and the upper end of the chain is adapted to wind around a grooved sheave 51^a on the longitudinally extending shaft 58. This shaft is provided at its front end with a hand wheel in convenient reach of the operator, so that it may be rotated, and it is journaled in bearings supported upon cross bars 60 secured at their ends to the arched portions of the reaches. 61 designates a pawl and ratchet adapted to hold the said shaft at the requisite adjustment. A slotted guide 62 projects upwardly from the rear axle 2 and a guide arm 63 projects upwardly and rearwardly from the rear cross beam 26 and projects into the slot of the guide 62 so as to properly maintain the rear cross beam when it is being raised or lowered.

64 designates a pair of braces that are pivotally connected at their front ends to the extensible sections 17 of the front cross beam 14, and that are provided with hooks 65 at 95 their rear ends, adapted to be entered into any one of a series of apertures 66 formed in the horizontally extending portions of the longitudinal beams 24. When the machine is being carried from place to place and is not in actual operation, it is evident that the entire framework may be suspended in an elevated position from the vehicle. In the practical operation, the frame work is lowered to the desired elevation so as to scrape 100 and properly grade or otherwise work the road, as it is drawn forwardly along the road by either a traction engine or other prime mover, or a team of horses hitched to the tongue 16. By manipulating the hand levers 23 the framework may be extended or 110 contracted laterally, the required distance, the braces 64 being released from the longitudinal beams of the frame work during the operation of adjustment, and then engaging 115 again in one of the openings in the said pitman. From the foregoing description in connection with the accompanying drawings, it is evident that the slides will adjust themselves laterally, or they may be adjusted by 120 hand, when the frame work is extended or contracted, and that either side or both sides of the framework may be held at the proper operating depth or elevation along the road by actuating the worms and worm gears, or by otherwise rotating the shafts 37. It is also obvious that the rear end of the framework may be raised or lowered whenever desired. For instance, it may be lowered for 125 engagement with the ground so as to cut off 130

knobs or ridges, and drag dirt into low places for leveling the road, or the said rear end may be elevated for the purpose of allowing soil to escape from underneath the machine. As the machine is made in two parts, namely the vehicle and the framework, the former with its weight on the ground will hold the entire machine steady, and this result will also be accomplished partly by the sliding scraping blades 28.

Having thus described the invention, what is claimed as new is:

1. A machine of the character described, comprising a traveling support, a laterally extensible frame work suspended from said support, means for extending and contracting said frame work, and scrapers carried by the frame work.
2. A machine of the character described, comprising a traveling support, a frame work suspended from the support and consisting of a laterally extensible front cross beam, a rear cross beam, and rearwardly converging longitudinal beams hinged at their rear ends to the rear cross beam, means for extending and contracting the front cross beam, and grading or scraping devices carried by the frame work.

3. A machine of the character described, comprising a traveling support, a scraper framework suspended from the support, and means for raising the front and rear ends of the framework from the support, the means for raising the front end of the framework being independent of the means for raising the rear end.

4. A machine of the character described, comprising a traveling support, a scraper framework extended from the support, means for suspending the rear end of the frame work at different elevations from the rear end of the support, and means for raising and lowering, from the support, either side of the framework at the front thereof, one side independently of the other.

5. A machine of the character described, comprising a traveling support, a laterally extensible scraper frame work suspended from the support, means for extending and contracting the framework, and means for raising and lowering the front end of the frame work.

6. A machine of the character described, comprising a support, embodying front and rear traveling wheels and a front bolster and reaches, a scraper framework consisting of a rear cross beam suspended from the reaches, longitudinal beams hinged at their rear ends to the rear cross beam, and a laterally extensible front cross beam to which the front end of the longitudinal beams are connected, suspension devices connected to the longitudinal beams and supported from the bolster, and means for raising and lowering said suspension devices.

7. A machine of the character described, comprising a support, embodying front and rear traveling wheels and a front bolster and reaches, a scraper framework consisting of a rear cross beam suspended from the reaches, longitudinal beams hinged at their rear ends to the rear cross beam, and a laterally extensible cross beam to which the front end of the longitudinal beams are connected, suspension devices connected to the longitudinal beams, laterally movable slides supported by the bolster, and means for raising and lowering the suspension devices upon slides.

8. A machine of the character described, comprising a traveling support embodying front and rear axles, a front bolster, and reaches connecting said bolster with the rear axle, a scraper frame work consisting of a rear cross beam, longitudinal beams hinged thereto at their rear ends, and a laterally extensible front cross beam to which the front end of the longitudinal beams are connected, slides movable laterally on the ends of the bolster, shafts journaled in said slides, means for rotating said shafts, and flexible suspension devices adapted to wind on said shafts and connected at their lower ends to the longitudinal beams of the framework.

9. A machine of the character described, comprising a traveling support, front and rear traveling wheels, a bolster, reaches, a scraper framework consisting of a rear cross beam supported from the reaches, longitudinal beams hinged at their rear ends to the rear cross beam, and a laterally extensible front cross beam to which the front ends of the longitudinal beams are connected, slides movable laterally on the ends of the bolster, shafts having bearings in said slides, worm gears splined on said shafts, worms meshing with said worm gears, a support for said worms and means for turning the worms, flexible extension members adapted to wind on said shafts and connected at their lower ends to the longitudinal beams of the frame work, and means for holding the worm gears relatively stationary as the shafts are carried in and out on their slides.

10. A machine of the character described, comprising a traveling support, embodying front and rear traveling wheels and axles therefor, a front bolster, reaches connecting the front bolster with the rear axle, said reaches being provided with arched portions near their rear ends, cross beams connected to the said arches, a shaft journaled in said cross beams, means for turning said shaft, and flexible suspension devices adapted to wind on said shaft, a scraper framework, adjustable suspension devices adapted to support the front end of the frame work from the bolster, and a connection between the framework and the suspension devices,

at the rear end of the reaches, the framework extending into the arched portions of said reaches.

11. A machine of the character described, comprising a traveling support, a scraper framework suspended from said support and including a main cross beam which extends in front of the support, a draft tongue secured to said front cross beam, means for raising and lowering the framework on the support, coupling irons connected to the front cross beam, a slotted vertically extending guide supported on the front end of the traveling support, the coupling irons extending into the slot of the guide, the framework also embodying a rear cross beam, and the traveling support embodying reaches having arched portions accommodating the said rear cross beam of the frame work, a slotted guide secured to the rear axle and extending upwardly therefrom, a guide arm secured to the rear cross bar of the frame work and extending into the slot of said last named guide, and means for raising and lowering said framework from the traveling support.

12. A machine of the character described comprising a traveling support, a scraper framework suspended from the support, and means on the support for raising and lowering the framework, said framework consisting of a rear cross beam, longitudinal beams hinged at their rear ends to the cross beam, a front cross beam constructed in an intermediate section and two side sections, to which latter the front ends of the longitudinal beams are connected, coupling sleeves slidably connecting the side sections of the front cross beam with the main section thereof, said side sections being provided with racks, pinions meshing with said racks and mounted in the main section of the front cross beam, ratchets secured on the shafts of said pinions, and hand levers fulcrumed to said shafts and provided with double pawls designed for engagement with the said ratchet wheels.

13. A machine of the character described, comprising a traveling support, a scraper frame work suspended from said support, means on the support for raising and lowering the framework, consisting of a rear cross beam, longitudinal beams hinged at their rear ends to the rear cross beam, and an extensible front cross beam to which the front ends

of the longitudinal beams are connected, means for extending and retracting the front cross beam, and braces pivotally connected to the front cross beam, the longitudinal beams being provided with a series of apertures in any one of which said braces are designed for engagement.

14. A machine of the character described, comprising a traveling support, a scraper framework supported thereby, and intermediate front and rear cross beams and longitudinal beams connecting the same, the said longitudinal beams being provided near their front ends with inwardly converging portions, and scrapers carried by said longitudinal beams at the juncture of said portions with the main portions of said beams.

15. A machine of the character described, comprising a traveling support, a scraper framework, a vertically adjustable suspension connection between the rear end of the frame work and the rear end of the support, flexible suspension members connected to the frame work near the front end of the latter, shafts carried by the support and upon which said flexible suspension members are adapted to wind, worm gears carried by said shafts, worms mounted on the support and meshing with the said worm gears, and means for turning said worms.

16. A machine of the character described, comprising a traveling support, a scraper framework, a vertically adjustable suspension connection between the rear end of the frame work and the rear end of the support, flexible suspension members connected to the frame work near the front end of the latter, shafts carried by said support and upon which said flexible suspension members are adapted to wind, worm gears on said shafts worms meshing with said worm gears, and supporting brackets in which the shafts of the worms are journaled, said brackets being forked and provided with an extensible member, and means for raising and lowering said member whereby to carry the worm out of and into engagement with the worm gear.

In testimony whereof I affix my signature in presence of two witnesses.

STEPHEN W. SMITH. [L. S.]
